METHOD AND APPARATUS FOR MAKING
WIRE FRAMES FOR CANDLE HOLDERSLeo Weiss, Brooklyn, N. Y., assignor of one-
twentieth to N. D. Q. Specialty Corporation,
Brooklyn, N. Y., a corporation of New York

Application March 8, 1935, Serial No. 9,990

9 Claims. (Cl. 140—71)

This invention relates to the method and apparatus for making wire frames for candle holders.

The object of the invention is the production of the wire frames of candle holders, comprising each a helical socket portion for the insertion of a candle and a shank to be inserted into a cake and the like.

The second object of the invention is the production of wire frames having helical socket portions, with means for pre-bending the wires of the frames before forming said socket portions, to avoid excessive resistance when the said socket portions are formed.

This application is a continuation in part of my application for Method and apparatus for making candle holders, Serial Number 733,068, filed June 29th, 1934.

In the accompanying drawings Fig. 1 represents a top plan view of apparatus for making wire frames for candle holders; Fig. 2 shows an extension of Fig. 1 on a reduced scale; Fig. 3 is a front view of Fig. 2; Fig. 4 indicates a section of Fig. 5 on the line 4.4; Fig. 5 represents a section of Fig. 4 on the line 5.5; Fig. 6 shows an enlarged side view partly in section of an element of Fig. 4; Fig. 7 indicates an enlarged vertical section of an element of Fig. 4; Fig. 8 shows a section of Fig. 7 on the line 8.8; Fig. 9 represents an elevation of one of the wire frames; Fig. 10 shows an enlarged section of Fig. 1 on the line 10.10; Fig. 11 is a right hand side view of Fig. 10; Fig. 12 represents a section of Fig. 10 on the line 12.12; Fig. 13 shows an enlarged section of Fig. 1 on the line 13.13; Fig. 14 is a section of Fig. 13 on the line 14.14; and Fig. 15 indicates a section of Fig. 13 on the line 15.15.

Referring to Figs. 1, 2 and 3, the apparatus for making the wire frames for candle holders is shown to comprise the main platform 25, which is supported on the angle iron legs 26 adjacent to the corners of said platform. From one of the legs 26 extends the horizontal angle iron support 27. A supporting brace 28 is provided for the angle iron support 27. A plurality of wire supply spools 30 are rotatively supported on the support 27. A journal bracket 32 having the hub end 33 extends from the support 27. A journal pin 34 extends through the hub end 33. An arm 35 is fastened to the lower end of the pin 34 and an operating link 36 is pivoted to the arm 35. The link 36 is pulled forward and back, by means not shown. A second journal bracket 40 having the hub end 41 extends from the support 27. A journal pin 42 extends through the hub end 41.

Ball cranks each having the hub 46, the short arm 47 and the long arm 48, have their hubs 46 fastened to the upper ends of the journal pins 34 and 42. A link 50 connects the arms 47 and a supporting plate 51 connects the long arms 48. A plurality of flanged guide rollers 53 are rota-

tively supported on the supporting plate 51. Guide pins 54 adjacent to the peripheries of the rollers 53 extend from the supporting plate 51. By moving the operating link 36 equal lengths of the wires 55, 56, 57 and 58 are simultaneously drawn from the spools 30.

Upon the main platform 25 are supported a pair of oppositely positioned journal brackets 59, having the upper journal bearings 60 and the lower journal bearings 61. In the journal bearings 60 are journaled the rollers 63 and 64, which have the circumferential V shaped grooves 65. In the journal bearings 61 is journaled the roller 70 having the circumferential V shaped grooves 71. A pair of arms 72 have each one end fastened to the roller 70. The roller 73 having the circumferential grooves 74, and the roller 75 having the circumferential grooves 76, are journaled in the arms 72. It will be noted that the rollers 70, 73 and 75 are in a plane below the rollers 63 and 64. The arms 72 carry the supporting plate 78 in which are journaled the flanged guide rollers 79. Guide pins 80 extend from the plate 78 adjacent to the rollers 79. The wires 55 to 58 engage the guide rollers 79. From the arms 72 extends the lower guide plate 80a, Fig. 3, which has in threaded engagement the adjusting screw 81, by means of which the supporting plate 78 can be tilted to different positions, to locate the rollers of the arms 72 in different positions to vary the distance between the upper and lower faces of the wires as they pass between the rollers of the arms 72 and the rollers 63 and 64. The wires 55, 56, 57 and 58 respectively extend over the roller 73, then under the roller 63, next over the roller 75, then under the roller 64, and finally over the roller 70. It will be noted that the wires 55 to 58, by reason of contacting with the rollers 63, 64, 70, 73 and 75 are straightened in parallel vertical planes.

A U shaped supporting bracket having the bottom wall 86 and the end walls 87, is supported upon and secured to the main platform 25. Similar supporting bars 88, 89, 90, 91 and 92 are slidably supported on the bottom wall 86. The said bars have rotatively connected thereto the flanged guide rollers 94, 95, 96 and 97. Similar adjusting screws 99 extend through the end walls 87 and bear against the ends of said supporting bars, to locate the rollers 94 to 97 in proper position to straighten the wires 55 to 58 horizontally in parallel planes.

Referring to Figs. 1, 10, 11 and 12, a wire feeding device is designated in its entirety by the numeral 102. The said device 102 comprises the pair of similar journal brackets 105. Each of the journal brackets 105 is provided with the upper journal bearing 106 and the lower journal bearing 107. An upper shaft 108 is journaled in the journal bearings 106 and a driving shaft 60

110 is journaled in the journal bearings 107. A third journal bearing 112 supports one end of the shaft 110. To the shaft 108 is fastened the central disc 115, having the circumferential 5 grooves 116 in its end faces and locking pins 118 extend from said end faces. The side walls of the grooves 116 are preferably knurled. Similar end discs 120 are fastened to the shaft 108. Each of the latter discs has a circumferential 10 groove 121 having its side wall preferably knurled and a locking pin 122 extends from one of its faces. Pairs of adjustable discs 125 are slidably supported on the shaft 108 between the discs 115 and 120. Each pair of the discs 125 15 are spaced from each other by the springs 126 and have openings for the locking pins 118 and 122. The discs 125 have the circumferential grooves 128, the side walls of which are preferably knurled.

20 A spur gear 130 is fastened to the shaft 108 and a spur gear 131 is fastened to the driving shaft 110. A locking clutch member 132 is integral with the spur gear 131. A drum 134 is fastened to the shaft 110. A wide spur gear 135 25 is slidably supported on the shaft 110. A clutch member 136 is integral with the spur gear 135. The clutch member 136 is adapted to lock with the clutch member 132. A spring 138 encircles the shaft 110 and bears between the spur gear 135 and the journal bearing 112. A journal bracket 140 is fastened to the main platform 25. A flange roller 141 is journaled to the bracket 140. A rack bar 145 is positioned between the spur gear 131 and the roller 141, with the teeth 30 of the rack bar 145 in mesh with the teeth of the spur gear 131. The rack bar 145 extends through the opening 148 in the platform 25. A journal bracket 150 extends from the lower face of the platform 25. An arm 151 has its ends 40 pivoted to the journal bracket 150 and to the lower end of the rack bar 145. An operating lever 152 has one end thereof pivoted to the arm 151. 45

With the reciprocations of the operating lever 152, by means not shown, the rack bar 145 is reciprocated, which turns the spur gears 130 and 131. While the rack bar 145 is moving downwardly the clutch members 132 and 136 remain locked, and the drum 134 and the discs 115 and 120 turn. The pairs of the adjustable discs 125 50 also turn with the shaft 108.

The wires 55 to 58 are led to and through the circumferential grooves of the rotating elements on the shaft 108, and by reason of the tension of the springs 126, clamp the said wires, which 55 are thereby independently fed through the feeding device 102. By means of the independent adjustability of the discs 125, even if the wires are of different diameters, they will however, be all simultaneously fed through the device 102 at 60 the same speed.

Referring to the Figs. 1, 13, 14 and 15, the shearing device for the wires 55 to 58 inclusive is designated in its entirety by the numeral 160. The said shearing device comprises the pair of 65 journal brackets 161, 162 and the journal bracket 163, all of which extend up from and are fastened to the main platform 25. In the journal brackets 161 and 162 is journaled the shaft 165, on which is fastened the U shaped arm 166 having the depending portion 167. A plurality of guide tubes 168 having the shearing ends 169 for the reception of the wires 55 to 58 are positioned in the portion 167. Depending journal brackets 170 extend from the arm 166. A shaft 171 has its 70 ends supported in the journal brackets 170. On

the shaft 171 are supported supporting blocks 172. At the upper portion of each supporting block 172 is indicated the U shaped cavity 176. The blocks 172 are suspended from the shaft 171. Screw 178 carried by the shaft 171 extends through the cavities 176. Through each of the supporting blocks 172 at the lower portion thereof extends an elongated guide tube 180 and which are normally in line with the guide tubes 168. In the upper end of the journal bracket 163 is 10 journaled the shaft 182, which is rotated by means not shown. A cam 183 is fastened to the shaft 182. A roller 184 is journaled to one end of the arm 166, and said roller 184 contacts with the cam 183. A spring 185 has one end fastened 15 to the apparatus and its other end is fastened to the arm 166. The shearing device 160 is operated by turning the shaft 182, by means not shown. The cam 183 contacting with the roller 184 swings the arm 166 and the shearing ends 20 169 of the guide tubes 168 shear off the wires that are positioned in the guide tubes 168 and 180. The said wires enter the guide tubes 180 after leaving the wire feeding device 102. When the arm 166 swings the supporting blocks 172 on the 25 shaft 171, the amount of swing is controlled by the screws 178 when they contact with the upper and lower walls of the cavities 176. The blocks 172 follow the inclination of the wires when the latter are swung out of line, by reason of the 30 swinging of the arm 166 and thereby kinks in the wires are avoided.

Referring to Figs. 1, 4 and 5 a supporting bracket is designated in its entirety by the numeral 210. The bracket 210 comprises the body 35 portion 212 having longitudinal openings 213 and is provided with the feet 214 which are supported upon and fastened to the main platform 25. From the body portion 212 extends the vertical wall 216. The wall 216 has integral therewith a 40 pair of journal hubs 222. A journal hub 223 is also integral with the wall 216. In the body portion 212 are openings 224, one of which is shown.

An initial bending device is designated in its entirety by the numeral 225. The device 225 comprises a pair of shafts 227. The latter shafts are supported in the hubs 222. From the shafts 227 depend the arms 228, which at their lower ends are connected by the angle iron guide 229 having the guide slots 230. To one of the shafts 227 50 is fastened the crank arm 232 and the latter has pivoted thereto the link 233 which is moved by means not shown. In the openings 224 are journaled a plurality of tubular guide spindles 235, each having a guide slot 236. One of said 55 spindles is provided for each of the wires 55 to 58. To each of the spindles 235 is fastened a spur gear 240. Shearing bushings 241 having the shearing ends 241a are tightly secured in the openings 224.

Referring to Figs. 4 and 5, a driving device is designated in its entirety by the numeral 242. The said driving device comprises a pair of journal brackets 243 which extend up from the main platform 25. A shaft 245 has its ends journaled 65 in the journal brackets 243. A large spur gear 246 is fastened to the shaft 245 and has integral therewith the clutch member 247. A spur gear 248 is carried on the shaft 245 and has integral therewith the clutch member 249, which is adapted to engage the clutch member 247. A spring 250 70 encircles the shaft 245 and bears between the journal bracket 243 and the spur gear 248. A pair of journal brackets 252 extend up from the main platform 25 and have journaled therein the 75

shaft 253, to which is fastened the flange roller 254. A rack bar 255 is interposed between the roller 254 and the spur gear 248 with which latter it is in mesh. In the journal hub 223 is journaled the shaft 260, to which are fastened a pair of arms 261. In the arms 261 is journaled the bending shaft 266. To one end of the shaft 260 is fastened the arm 267 which latter has journaled thereto the roller 268. A grooved cam 270 on the shaft 271 coacts with the roller 268.

The rack bar 255 is vertically reciprocated by means not shown. With the upward movements of the rack bar 255, the spur gear 248 turns and thereby the large spur gear 246 transmits rotation to the spur gears 240. With the rotations of the spur gears 240 the guide spindles 235 are turned. The wires 55 to 58 after they leave the feeding device 102 enter and move through the guide tubes 180 and from the latter enter and pass through the guide tubes 168. The wires 55 to 58 then enter the shearing bushings 241 and pass through the guide spindles 235. By the operation of the shearing device 160 the wires are sheared by the shearing ends 169 and 241a which are adjacent to each other. After predetermined lengths of the wires 55 to 58 have been sheared the feeding device 102 moves additional lengths of wires through the bushings 241, which push the previously cut lengths of wires through the guide spindles 235. As the wires leave the spindles 235, the bending shaft 266 has previously been positioned below the guide spindles 235. While the lengths of wires are pushed forwardly the bending shaft 266 swings upwardly and bends the cut off portions of the wires 55 to 58 as indicated in dotted lines in Fig. 4. The said bending occurs at the inner ends of the slots 236.

In the body portion 212 is supported the slide plate 275 which at its front end has integral therewith a bracket 276. The said bracket has formed therewith a plurality of cup shaped housings 277, each of which has the opening 278 in its vertical wall, and the T shaped opening 279 having the guide wall 280 and the guide wall 281 in its roof which join with the opening 278. A link 282 is pivoted to the slide plate 275. The link 282 is actuated by means not shown to reciprocate the slide plate 275.

Referring to Fig. 9 the wire frame 288 of the candle holder is shown to comprise the helical socket portion 290, and from the latter extends the shank 291. When the slide plate 275 positions the housings 277 with their openings 278 around the forward ends of the spindles 235, the walls 280 are in line with the inner ends of the slots 236, and the wires are bent further to vertical positions. While the walls 280 are bending the wires upwardly, they also position said wires in the guide slots 230. When the housings 277 with their walls 280 reach the end of their stroke in a direction opposite the arrow A, Fig. 4, the angle iron guide 229 begins to horizontally reciprocate and initially bends the wires around the forward ends of the spindles 235. The angle iron guide 229 in this instance bends a pair of wires in one direction and during the opposite movement of the angle iron guide 229 releases the said wires and bends another pair of the wires in an opposite direction. At the same time each pair of the spindles 235 are rotating at a speed slower than the reciprocations of the guide 229 in directions opposite to the bending of the wires. The purpose of the steps just described is to reduce the power required to form the helical socket portions 290 of the frames 288.

As the spindles 235 turn the slide plate 275 simultaneously moves forwardly in the direction of the arrow A. The vertical legs of the wires bear against one of the walls 281 of the T shaped openings 279, and are thereby carried forwardly. At the same time the helical socket portion 290 of the wire frames are formed around the forward ends of the spindles 235.

It will be noted that a portion of each length of wire remains within the bore of its guide 10 spindle 235, while its helical socket portion is being formed.

Referring to Figs. 1, 4 and 5, a spindle operating device is designated in its entirety by the numeral 300. The device 300 comprises the supporting frame 301, having the row of journal bearings 302 and the row of journal bearings 303. In each accompanying pair of said bearings are journaled the spindles 304.

Each of the spindles has provided therefor an 20 expansion support. Each expansion support, see Figs. 7 and 8, of the spindles 304 comprises the fixed tapered semi-cylindrical portion 308, which is a continuation of the spindle 304. A second tapered semi-cylindrical movable portion is shown 25 at 309 and is normally spaced from the portion 308. A plate spring 310 has one end fastened to the spindle 304 by the screw 311 and its other end is fastened to the portion 309 by the screw 312. By virtue of the construction just described, 30 the portion 309 is in movable relation to the portion 308, and thereby the outer diameter of the said portions 308 and 309 is variable. To the spindles 304 are fastened the driving gears 315 and 316. Supplemental journal bearings 318 and 319 are integral with the device 300, and have journaled therein the shaft 320. On the shaft 320 is fastened the driving gear 321 which meshes with the gear 315. A spur gear 322 is also fastened to the shaft 320. A pair of journal bearings 327 extend from the platform 25. A shaft 328 is journaled in the journal bearings 327 and has fastened thereto the flange roller 329. A rack bar 330 is interposed between the roller 329 and the gear 322, with which latter it is in mesh. 45 Means not shown are provided for reciprocating the rack bar 330. On the shaft 320 is fastened a third gear 331. A journal bracket 335 extends from the platform 25 and has fastened thereto a pair of studs 336. Idler gears 338 and 339, in 50 mesh with each other, are supported on the studs 336. A driven gear 340 fastened to one of the spindles 304 is in mesh with idler gear 338. An idler gear 342 on one of the spindles 304 is in mesh with the gear 340. A driven gear 343 fastened to one of the spindles 304 is in mesh with the gear 342. A pair of journal brackets 347 are integral with the device 300 and have journaled therein the shaft 348. An arm 349 has one end fastened to the shaft 348. A link 350 is pivoted to the upper end of the arm 349 and rocks the latter by means not shown. A plate 351 is fastened to the shaft 348. Adjusting screws 352 with lock nuts extend from the plate 351. A cover 360 is provided for the spindle operating device 300.

Referring particularly to Fig. 4 after the frames 288 have been formed with their helical socket portions 290 they are supported on the guide spindles 235. Next the slide plate 275 moves in the direction of the arrow A, and the helical socket portions 290 in the housings 277 are located around the forward ends of the spindles 304. Before the portions 290 are located around the spindles 304, the screws 352 by virtue of the 75

swing of the plate 351, the said screws 352 bear against the movable cylindrical portions 309, to reduce the outer diameters of the portions 308 and 309 to freely receive the helical socket portions 290. The screws 352 now separate from the guide spindles 304 and the latter tightly support the helical socket portions 290 of the frames 288, resulting from the separation of the portions 309 from the portions 308. The slide plate 275

10 now moves in a direction opposite to the arrow A, and the foregoing steps are repeated to form succeeding lots of wire frames 288. The frames 288 are removed from the spindles 304 by means not shown to be used for candle holders.

15 Various modifications may be made in the invention and the present exemplifications is to be taken as illustrative and not limitative thereof.

Having described my invention I claim:

1. In a feeding device for an apparatus the combination of a rotating drum, a shaft parallel to the longitudinal axis of the drum and rotating therewith, discs having circumferential grooves in their end faces fastened to the shaft, pairs of adjustable discs supported on the shaft 20 and having circumferential grooves coacting with the grooves of the other discs, connections between each adjustable disc and one of the other discs, the circumferential surface of the drum adjacent to the circumferential surfaces of the

25 discs and flexible means between the pairs of adjustable discs, the grooves of the discs adapted to grip wires of various diameters to feed them through the feeding device.

2. In a feeding device the combination of a 30 rotating drum, a shaft parallel to the longitudinal axis of the drum and rotating therewith, discs having circumferential knurled grooves in their end faces fastened to the shaft, pairs of adjustable discs supported on the shaft having circum- 35 ferential knurled grooves coacting with the adjacent grooves of the other discs, connections between each adjustable disc and one of the other discs to slidably connect them, the circumferential surface of the drum adjacent to the circum- 40 ferential surfaces of the discs and flexible means between each pair of adjustable discs to automatically locate them in operative position.

3. In a shearing device the combination of an 45 oscillating arm, a plurality of guide tubes each 50 having a shearing end supported in the arm, a shaft carried by the arm and spaced therefrom, a plurality of supporting blocks suspended from said shaft and an elongated guide tube supported in each supporting block, the axis 55 of each of the latter guide tubes normally coaxial with the axis of one of the guide tubes of the arm.

4. In a shearing device the combination of an 60 oscillating arm, a plurality of guide tubes each 65 having a shearing end supported in the arm, a shaft fastened to the arm and spaced therefrom, a plurality of supporting blocks suspended from said shaft, an elongated guide tube supported in each supporting block, each elongated 70 guide tube normally coaxial with one of the other guide tubes and means to limit the extent of any oscillations of the suspended supporting blocks, each elongated guide tube with its coaxial guide tube adapted to have a wire fed therethrough.

5. In an apparatus the combination of a bracket having an opening therethrough, a shearing

bushing having a shearing end in the said opening, a tubular guide spindle journaled in said opening coaxial with said shearing bushing, a portion of said spindle extending outside of said bracket, said portion of the spindle having a 5 guide slot, means to rotate the spindle, an angle iron guide having a guide slot above the guide slot in the spindle and means to reciprocate said guide over the spindle during the rotations of the latter.

6. In an apparatus the combination of a bracket having a plurality of openings, a shearing bushing in each opening, a tubular guide spindle journaled in each opening coaxial with the shearing bushing therein, a portion of each spindle 10 extending outside of said bracket, each of said portions having a guide slot, a spur gear fastened to each spindle, said spur gears in mesh with each other, means to turn said spur gears and thereby rotate the spindles, an angle iron guide having 15 a plurality of guide slots above said spindles and means to reciprocate said angle iron guide during the rotations of the spindles, each of said bushings and its coaxing guide spindle adapted to have a length of wire forced therethrough, 20 the front end portion of each wire adapted to extend through one of the guide slots of the angle iron guide to be bent during the reciprocations of the said angle iron guide.

7. In an apparatus the combination of a plurality of rotating tubular spindles each having a guide slot, an angle iron guide having a plurality of guide slots above said spindles, means to reciprocate said angle iron guide during the 25 rotations of the spindles, each of said spindles adapted to have a length of wire forced therethrough, a bending shaft adjacent to said angle iron guide and means to actuate said shaft to bend the forward end of each length of wire and locate it in one of the guide slots of said 30 angle iron guide.

8. In an apparatus the combination of a plurality of rotating tubular guide spindles each having a guide slot, said spindles each adapted to have a length of wire forced therethrough, 35 means to reciprocate and bend the forward end of each wire as it is forced through its spindle, a reciprocating slide plate parallel to and spaced from said spindles and a plurality of cup shaped 40 housings extending from said reciprocating slide plate, each of said housings having an opening coaxial with one of said spindles, and having a second opening leading to the former opening, the said housings positioned around the forward 45 ends of said spindles by the said slide plate to 50 position the wires in said second openings of the 55 housings, the rotations of the spindles forming a helical socket portion for each length of wire while the slide plate moves the housings from 60 said spindles.

9. The method of making a plurality of frames for candle holders consisting in simultaneously 65 pulling equal lengths of wires from sources of supply, simultaneously straightening the wires in the planes of their longitudinal axes and then 70 in a plane at right angles to their longitudinal axes, simultaneously shearing the wires to equal predetermined lengths and simultaneously forming a helical socket portion at one end of each 75 wire.

LEO WEISS.
